US00D942829S

(12) **United States Design Patent** (10) **Patent No.:** **US D942,829 S**
(45) **Date of Patent:** **** Feb. 8, 2022**

(54) **POWER TOOL**

(71) Applicant: **ATLAS COPCO INDUSTRIAL
TECHNIQUE AB**, Stockholm (SE)

(72) Inventors: **Apurba Pawar**, Stockholm (SE);
Henrik Sohlman, Skogås (SE)

(73) Assignee: **ATLAS COPCO INDUSTRIAL
TECHNIQUE AB**, Stockholm (SE)

(**) Term: **15 Years**

(21) Appl. No.: **29/731,640**

(22) Filed: **Apr. 16, 2020**

(30) **Foreign Application Priority Data**

Oct. 17, 2019 (EM) 007038625-0005
Oct. 17, 2019 (EM) 007038625-0006

OTHER PUBLICATIONS

Design U.S. Appl. No. 29/731,625; First Named Inventor: Francisco Lindoro; filed Apr. 16, 2020; Title: "Power Tool".

(Continued)

Primary Examiner — Austin Murphy

(74) *Attorney, Agent, or Firm* — Holtz, Holtz & Volek PC

(57) **CLAIM**

The ornamental design for a power tool, as shown.

DESCRIPTION

The patent or application file contains at least one drawing executed in color. Copies of this patent or patent application publication with color drawing(s) will be provided by the Office upon request and payment of the necessary fee. The entire contents of U.S. Design application Ser. No. 29/731,637, filed on Apr. 16, 2020, are incorporated herein by reference.

FIG. 1 is a front, top, right side perspective view of a power tool showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a rear elevational view thereof;

FIG. 7 is a front elevational view thereof; and,

FIG. 8 is a rear, top, left side perspective view thereof.

1 Claim, 8 Drawing Sheets

(8 of 8 Drawing Sheet(s) Filed in Color)
